UNITED STATES PATENT OFFICE.

WILLIAM T. HORMES, OF GOVANS, MARYLAND, ASSIGNOR TO SOLOMON HIMMEL, OF BALTIMORE, MARYLAND.

DISPLAY-RACK.

1,284,685.

Specification of Letters Patent. Patented Nov. 12, 1918.

Application filed July 1, 1915. Serial No. 37,545.

To all whom it may concern:

Be it known that I, WILLIAM T. HORMES, a citizen of the United States, residing at Govans, in the county of Baltimore and State of Maryland, have invented new and useful Improvements in Display-Racks, of which the following is a specification.

This invention is a device for displaying or exhibiting garments, although not limited to this class of goods, and relates to that type of display devices wherein a rotatably mounted rack is employed for supporting the goods to be displayed, and normally inclosed within a case or compartment. Such cases or compartments are usually constructed with glass walls or panels, so that the goods on display may be readily seen by prospective customers passing the same, and at the same time be protected from dust and promiscuous handling. In view of the fact that economy of floor space demands that the area occupied by the case be as small as possible, it is usually customary to construct the case of oblong shape, with the rack or supporting member conforming to this shape, being of a length greater than the width of the case. When it is desired to more closely inspect the articles on display, and in order that the rear and front rods of the rack may be rendered readily accessible, the rack is so mounted as to be moved to a point near the front of the case, a sufficient distance to permit the ends of the rack to swing in front of the rear wall or panel of the case, when the rack is rotated to reverse the positions of the rods. One of the objects of the invention is to provide a rack of this character, constructed to permit the garment supporting member to move in and out of the case or compartment for a predetermined distance, and to prevent rotation of the rack until it reaches its forward position. A further object is to provide means which will permit of ready reversal of the garment supporting rods when the rack has been moved to its forward position.

The invention will be hereinafter fully set forth and particularly pointed out in the claims.

In the accompanying drawing:—

Figure 1 is a plan view illustrating the improved display rack, the walls of the case or compartment being shown in section.

Fig. 2 is a sectional view illustrating the controlling member.

Fig. 3 is an enlarged detail view of the guide channel.

Figs. 4 and 5 are diagrammatic views illustrating the operation of the invention.

Fig. 6 is a detail view illustrating a slight modification.

Referring to the drawing, 10 designates a case or compartment of any suitable or preferred construction, that illustrated being provided with glass panels forming the end and rear walls, respectively, the front being closed by suitable movable sections 11 forming doors. The bottom 12 of the case or compartment, is provided with a channel 13, the upper edges of which are provided with guides 14, between which the carriage 15, is mounted to reciprocate. If desired, the guides 14 and carriage 15, may be provided with complementary shoulders 16, arranged at the proper angle to receive 17 the anti-friction balls 17.

Rotatably supported in suitable manner by the carriage 15, is a shaft 18, to which is attached a cross head 19, which is provided with means for supporting the rods 20, 80 which serve to support the garments, or other articles that may be desired. The shaft 18 extends downwardly through the carriage 15 and is provided at its lower end with a crank arm 21, to the free end of 85 which is attached a depending pin or roller 22, said arm and roller serving as a controlling member to control the rotation of said shaft. The roller 22 of the controller member extends downwardly into a guide 90 channel provided with a main portion running from front to rear of the case or compartment, parallel with the side walls of the channel 13, as indicated at 23, the forward end of said channel being provided 95 with branches 24 and 25 forming an approximately semi-circular supplemental channel, the walls of which are curved on

an arc struck from the axis of shaft 18, when the latter is in its extreme forward position, and upon a radius corresponding to the length of the arm 21. The guide channel is located upon the bottom of the channel 13 as shown.

In operation when the roller 22 is in alignment with the straight portion 23 of the channel, the carriage 15 may be reciprocated 10 in its guides, toward and away from the rear wall of the case. Just as soon as said roller enters the channel 23, rotation of the shaft 18 is prevented for the reason that any force tending to rotate said shaft at that time, also 15 tends to swing the arm 21 in an arc of a circle with the shaft 18 as the center. It is evident, however, that as the roller 22 on the end of the crank arm 21 is held by the channel 23, rotation of the rack is prevented. 20 When the carriage has been moved to its forward position, the shaft 18 may be rotated by means of the rods 20, in the usual and well-known manner, with the result that the arm 21 will swing the roller 22 into either 25 of the branches 24 or 25, according to the direction of rotation, until said roller strikes the end of the branch, whereupon travel of the outer end of arm 21 is arrested. As rotative pressure on shaft 18 continues, roller 22 acts as a fulcrum, causing arm 21 to swing thereon and carry the shaft 18 inwardly parallel with the straight or main branch 23 of the guide, the parts successively moving from full line position to the several dotted line positions illustrated in Fig. 4, roller 22 continuing to act as a traveling fulcrum, guided by the curved branch 24 or 25, as the case may be, until the shaft 18 has been rotated 180 degrees. This movement has 40 placed said shaft somewhat back of its original outermost position, and the rear garment rod will then be at the front so that the rack can be returned into the case without further rotative movement. When it is 45 desired to again reverse the rack it is pulled to the front of the case or compartment and when the rotative force has been applied to the shaft 18, the roller 22, swinging into either of the branches 24 or 25, will partially 50 reverse the positions of the hanging rods, and when the roller 22 strikes the end of the branch, continued rotative pressure applied to the shaft 18 will completely reverse the rack and at the same time the roller 22 acting as a fulcrum, will cause the carriage to 55 move to the extreme forward position. The roller 22 will then be positioned ready for the return of the rack into the case.

In Fig. 6 is illustrated a slight modification, in which the guide channel 26 is provided with but one branch 27. In this form of the invention, reversal of the rack is impossible except in one direction.

It will be understood that while the guide groove has been illustrated and described as 65 located in the bottom of the channel 13, the invention is not limited to this specific location, except as determined by the scope of the appended claims.

Having thus explained the nature of my 70 invention, and described an operative manner of constructing and using the same, although without attempting to set forth all of the forms in which it may be made, or all of the forms of its use, what I claim is:— 75

1. An improvement in display racks comprising a rotatable rack member, a reciprocable support therefor, a crank arm attached at one end to said rack member, a main guide extending parallel with the line 80 of reciprocation of said support and engaging the free end of said crank arm, said guide having a lateral branch curved in the arc of a circle of a radius corresponding with the length of said crank arm, the free end of 85 the crank arm being movable into said branch during a one hundred and eighty degree rotation of the rack member, said branch having an abutment at its outer end to arrest travel of the free end of the crank 90 arm at the completion of approximately ninety degrees of rotation of the rack member and so positioned that when force is applied to said rack member to continue said rotation, the free end of the crank arm becomes a traveling fulcrum co-operating with the branch to reciprocate the rack member in one direction, said crank arm and said branch being of a relative length to cause said reciprocation to withdraw the free end 100 of the crank arm to the intersection of the lateral branch with the main branch at the completion of said one hundred and eighty degrees rotation.

2. An improvement in display racks comprising a rotatable rack member, a reciprocable support therefor, a crank arm attached at one end to said rack member, a main guide channel extending parallel with the line of reciprocation of said support and engaging 110 the free end of said crank arm, said guide channel having at one end two branches extending laterally therefrom and curved in the arc of a circle of a radius corresponding with the length of said crank arm, said 115 branches forming an approximately semi-circular supplemental channel, the free end of the crank arm being movable laterally in either direction into said supplemental channel, during a one hundred and eighty degree rotation of the rack member, depending upon the direction of rotation, each branch having an abutment at its outer end to arrest travel of the free end of the crank arm at the completion of approximately ninety 120 degrees of rotation of the rack member and 125

so positioned that when force is applied to said rack member to continue the rotation, the free end of the crank arm becomes a traveling fulcrum coöoperating with the supplemental channel to reciprocate the rack member in one direction, said crank arm and each of said branches being of a relative length to cause said reciprocation to withdraw the free end of the crank arm to the 10 intersection of the supplemental channel

with the main guide channel at the completion of said one hundred and eighty degrees rotation.

In testimony whereof I have hereunto set my hand in presence of two subscribing witnesses. 15

WILLIAM T. HORMES.
